ELECTROMAGNETIC DEVICE

William C. Roe, Elyria, Ohio, assignor to Robert
B. Brewer, Cleveland, Ohio

Application April 28, 1934, Serial No. 722,936

3 Claims. (Cl. 177—7)

My invention relates to electro-magnetically operated mechanisms and relates more particularly to striker mechanisms for use with chimes or other musical instruments.

5 It is an object of this invention to produce a maximum power stroke from a limited amount of applied electrical energy.

Another object of the invention is to construct a striker mechanism or the like for musical instruments employing a vibratable element, wherein the rebound speed of the striker is greater than the rate of vibration of the vibratable element when the latter is struck.

15 My invention has for another one of its objects to eliminate extraneous noise and vibration of an armature actuated electro-magnetically, and to further eliminate substantially all alternating hum or chatter.

A still further object of the invention is to 20 produce an electro-magnetically operated striker mechanism having the above desired characteristics, and which is extremely simple in construction and design and which is further equally well adapted for use with both alternating and direct current.

25 Other objects and advantages of my invention will become more apparent as the following description of two embodiments thereof progresses, reference being made to the accompanying drawing in which like reference characters are employed to designate like parts throughout the same.

In the drawing:

Figure 1 is a vertical section of a musical instrument such as a chime, showing one form of my invention applied in use, the electro-magnetically operated striker mechanism being shown in side elevation and housed within a resonance chamber;

40 Figure 2 is a side elevation of the same embodiment of my invention shown in Figure 1 and shows the relative positions of the armature and magnet cores when the magnets are de-energized;

45 Figure 3 is a similar view of the same embodiment of the invention showing the relative positions of the armature and magnet cores at the beginning of the power stroke, as when the magnets are energized;

50 Figure 4 is still another view of the same embodiment illustrating the position of the armature at the peak of the power stroke;

55 Figures 5, 6 and 7 illustrate a second embodiment of my invention and correspond respec-

tively to Figures 2, 3 and 4 illustrating the first embodiment; and

Figure 8 is a front elevation of the device shown in Figure 2.

It is to be understood that while I have shown but two embodiments of my invention in the drawing and have shown the same applied in use in connection with a musical instrument, such as a chime, that the invention is not to be considered to be limited to such use or to the specific structure shown in the drawing, since other adaptations of the invention coming within the scope of appended claims and the purpose of the invention readily may be made.

Referring now more particularly to Figures 1, 2, 3, 4 and 8 I will proceed to describe the particular embodiment illustrated therein.

In Figure 1 I have shown this embodiment applied in use in connection with a musical chime in which 1 represents an elongated tubular resonance chamber. The resonance chamber 1 is provided with a restricted opening 2 intermediate its ends in one face thereof, through which the striker 3 is projected to momentarily strike the vibratable element 4. It is to be noted that in the present embodiment the striking mechanism is mounted as a unit entirely within the resonance chamber 1, and that the vibratable element or reed 4 is mounted on the outside of the resonance chamber and in spaced relation thereto by means of the brackets 5, the reed 4 overlying the restricted opening 2 and located in the path of movement of the striker 3. The reed 4 is suspended from the brackets 5 by any suitable means such as the springs 6, which may be similar to the type of spring shown in my copending application, Ser. No. 674,338, filed June 5, 1933. The present invention, however, relates more particularly to the striker mechanism which is designed as a unit to be mounted within the resonance chamber 1.

In carrying out the invention as illustrated in the drawing the coils 7 are mounted side by side on a plate 8 by means of the bolt or screw 10. A layer of fiber or other insulating material 11 is interposed between the plate 8 and the plate 27 and each of these elements is firmly clamped or secured together when the bolt 10 is tightened to rigidly support the coils 7 and bracket 12 thereon. The armature supporting bracket 12 is substantially L-shaped in cross section, the base comprising a pair of forwardly extending supports 13, one extending forwardly below each of the magnet coils and spaced from each other to provide ample space between them.

for the spring 14 and for the depending portion of the armature 15. The forward ends of the bracket members 13 are bent upwardly as at 16 to provide forward stops on opposite sides of the 5 armature body 17 (see Figure 4) during the approach of the armature to one of its extreme 10 limits of motion. It will be noted that the bracket members 13 are inclined first slightly upwardly as at 18 before terminating in the sharply upturned portions 16. In this manner 15 the slightly inclined surfaces function to help the spring 14 to withdraw or retract the armature to its normal position as shown in Figure 1 when the coils are de-energized.

15 The armature comprises a substantially T-shaped element, the portion 17 constituting the armature proper and being disposed within the electro-magnetic field of the poles 19 of the coils 7. The armature also includes an integral depending arm 15 to which is detachably secured at its lower end, the striker member 3. It is preferred that the striker element 3 be weighted sufficiently to give an effective stroke when the armature is actuated in response to the energization 20 of the magnets 1. The striker 3 is provided with a soft tip 20 of leather or other suitable material which is commonly used in such devices and is adapted to sharply engage the vibratable element 4 to deliver a sharp blow thereto. The 25 armature 15 carries a cross member 21 which is secured to its rear face by means of a screw 22. The member 21 is formed with oppositely disposed arms 23 which operate just below the under 30 surface of the bracket members 13 and serve as stops for the armature during its retraction or toward the backward limit of its motion as indicated in Figure 1. The member 21 terminates at its lower end in a hook 24 to which one end of the retraction spring 14 is attached, the opposite 35 end of the spring 14 being attached to the bracket 12 as at 25. It is sufficient that the spring retract the weighted armature to a position such as indicated in Figure 1 and to retain the same in that position while the magnets 7 40 are de-energized.

The coils 7 may be connected in series electrically and their free ends are connected to a pair of insulated binding posts 26 projecting from the rear of the mounting plate 27.

50 The resonance chamber 1 is provided with an opening in one of its walls for receiving the striker unit for mounting within the chamber. In the embodiment illustrated this opening is indicated at 28 in the rear wall of the chamber 55 1 and at the upper end thereof. It is to be understood, however, that this opening may be otherwise located in the chamber to suit various conditions if desired.

The lower end of the plate 27 is upset as at 60 29 to form a socket 30 with the rear wall of the chamber which it overlies when the unit is assembled within the chamber. Suitable screws 31 are provided to removably secure the plate 27 to the chamber.

65 The resonance chamber 1 may be suitably tuned to proper resonance with the period of the vibratable element 4 by means of the partition 32. This partition may be of soft material and is cut to fit the internal cross section of the 70 chamber. It is adjustable vertically within the chamber and may be fixed therein in proper adjustment by any suitable means. A similar member 33 may be inserted against the top wall of the chamber. By such construction internal 75 chatter or noise is substantially eliminated.

The operation of this embodiment of my invention may be described as follows:

The unit shown in Figure 8 is inserted through the opening 28 in the chamber 1 with the plates 9 and 27 closing the opening. This is clearly shown in Figure 1. The screws 31 are driven home to securely, but removably, fasten the unit in place. A source of electrical energy with a suitable switch (not shown) may be connected to the binding posts 26 and when the circuit is 10 closed the coils 7 will be energized.

Figures 2, 3 and 4 represent the three principal phases of the operation of the striker in delivering a sharp impact blow to the vibratable element 4. In Figure 2 the armature and striker are fully retracted by means of the spring 14. In this position the armature 17 engages the pole pieces 19 only in point contact along their lowermost edges. Energization of the coils 7 sets up a magnetic field at the poles which is sufficient to quickly draw the armature head 17 toward the pole pieces against the tension of the spring 14. It is to be noted that the armature rocks about the point contact at 34 to assume a position as in Figure 3, that is where the armature lies flat 20 against the pole pieces. The next position of the armature results from a further rocking of the same until it again is in point contact with the upper edges of the pole pieces as at 35 in Figure 25 4. This power stroke of the armature, the depending arm 15 and the striker 3 is accomplished while some portion of the armature is always in contact with the pole pieces, thereby reducing and 30 substantially eliminating chatter and noise or hum. This is particularly noticeable when the 35 device is operated by A. C. current. Furthermore by thus eliminating the air gap between the armature and the pole pieces at the start and during the stroke, the striking power of the striker 3 is materially increased. The contact of the 40 armature with the cores between points 34 and 35 eliminates the air gap and tends to first decrease and thus increase the magnetic leakage. The armature rocks on the cores and tends to draw to the point of greatest density of magnetic 45 flux. The inertia of the striker 3 carries the armature slightly beyond this point until it strikes the vibratable member 4, and against a portion of the magnetic pull of the cores which affects the armature in a reversed direction as a 50 rebound pull. This is illustrated in Figure 4 where the armature contacts only with the upper edge of the cores 19 as at 35. This is at the end of the power stroke and the magnetic pull of the cores will tend to pull the armature back toward 55 the normal position, constituting a rebound action.

As a result the striker is quickly retracted and such action is further assisted by the retracting spring 14. In the rebound movement of the 60 striker the magnetic pull, the spring 14 and the resiliency of the striker tip all contribute to a quick return of the striker at a speed which is faster than the return movement of the element 4 after it is struck.

65 The armature rests and slides upon the brackets 13 and is otherwise possessed of a freedom of movement within the limits defined by the coils or the stop 21 and the portion 16. Lateral freedom is also provided as indicated in Figure 8, 70 but very little lateral movement will be required.

In Figures 5, 6 and 7 I have illustrated a modification of my invention which is quite similar to the form illustrated in Figures 1 to 4 inclusive, except for the armature. In the present embodiment 75

ment the armature 40 is arcuate or curved in cross section or end elevation as indicated. In this manner the armature striker member will be caused to roll upon the cores 41 of the magnets when the latter are momentarily energized. As in the case of the first described embodiment, the armature 40 is at all times in contact with the pole faces or cores 41. The normal retracted position of this modified armature is shown in Figure 5 and at the beginning of the power stroke the armature is in but point contact as at 42 with the lower edge of the cores. When the magnets are energized the armature is caused to roll quickly as in Figures 6 and 7 to thrust 10 the striker 3 outwardly through the opening 2 in the resonance chamber and into sharp but momentary contact with the member 4.

When either embodiment is assembled as shown in Figure 1, the device constitutes a very compact simple structure, possessing a pleasing tone and readily adapted for various uses. For instance, the device may be used in place of a door bell or other call device, or it may be used as a ringer for telephones or the like. Because 20 of its simplicity of construction and easy manner of assembly, it is very economical to manufacture. I have found that devices embodying my invention can be operated with extremely low power consumption and because of this feature 25 the device is particularly useful as door alarms, since it will operate efficiently on from 1½ to 6 volts if desired.

Various changes in the details of construction and arrangement of parts may be made without departing from the spirit of my invention or the scope of the appended claims.

I claim:

1. A striker device for musical instruments and the like comprising a striker having a substan-

tial mass at one end, a support pivotally supporting said striker adjacent the other end, an electromagnetic means arranged to attract the end of the striker remote from said mass and beyond said support to oscillate said striker, said electromagnetic means having a core face lying in a plane intersecting that portion of the striker near its pivoted end when the striker is at rest whereby said means will exert its maximum pull when the striker is in the lowermost position of 10 its swing.

2. A striker device for musical instruments and the like comprising a striker having a substantial mass at one end, a support pivotally supporting said striker adjacent the other end, an electromagnetic means arranged to attract the end of the striker remote from said mass and beyond said support to oscillate said striker, said electromagnetic means having a core face lying in a plane intersecting that portion of the striker 15 near its pivoted end when the striker is at rest whereby said means will exert its maximum pull when the striker is in the lowermost position of 20 its swing, and a fulcrum remote from said support about which said striker may oscillate after 25 it has reached said lowermost position.

3. A striker device for musical instruments and the like including an electromagnet, an armature support associated therewith and extending below and beyond one end thereof, a striker suspended from the support and in slidably engagement therewith, said striker having an armature portion extending above the support and movable in the magnetic field of the electromagnet when the latter is energized, that portion of the 30 35 striker which is suspended below the support being provided with a weighted mass.

WILLIAM C. ROE.
